CLAIM

The ornamental design for a pool float, as shown and described.

DESCRIPTION

FIG. 1 is a perspective view of the claimed pool float;
FIG. 2 is a side view of the claimed pool float;
FIG. 3 is an opposite side view of the claimed pool float;
FIG. 4 is a back view of the claimed pool float;
FIG. 5 is a front view of the claimed pool float;
FIG. 6 is a top view of the claimed pool float; and,
FIG. 7 is a bottom view of the claimed pool float.
The broken lines are for environmental purposes only and form no part of the claimed design.
